UNITED STATES PATENT OFFICE.

CLINTON B. PIKE, OF BIRMINGHAM, ALABAMA, ASSIGNOR, BY MESNE ASSIGNMENTS,
TO JAMES THOMPSON & CO., OF NEW YORK, N. Y., A COPARTNERSHIP COMPOSED
OF JULIUS BUCHMAN AND EDWIN BUCHMAN.

CANOPY-FRAME BRACKET.

1,416,414.

Specification of Letters Patent. Patented May 16, 1922.

Application filed August 8, 1921. Serial No. 490,476.

To all whom it may concern:

Be it known that I, CLINTON B. PIKE, a citizen of the United States of America, residing at Birmingham, in the county of 5 Jefferson and State of Alabama, have invented certain new and useful Improvements in Canopy-Frame Brackets, of which the following is a specification.

This invention relates to an improved 10 bracket for the attachment of canopy frames to beds and the like, and its object is to obtain a more effective clamping engagement with various shapes and sizes of bed frames than is possible with the present canopy 15 supports.

More particularly it is the purpose of this invention to utilize a flexible band adapted 20 to have its ends drawn together by a clamp bolt as the means for clamping both the canopy support loop to a bent metal bracket plate and the bracket plate to the various 25 sizes and shapes of bed posts and like supports thus obtaining a positive mounting for the canopy frame itself as well as for its supporting bracket.

A further feature of my invention is the 30 adaptation of the bracket plate to be reversed and screwed to a post or support with the canopy frame loops interposed between it and the support and thus clamped rigidly 35 in place by the same means which mounts the bracket on its support.

My invention moreover comprises the 40 novel details of construction and arrangements of parts, which in their preferred embodiment only are illustrated in the accompanying drawings which form a part of this specification, and in which:—

Fig. 1 is a perspective view of a bed frame 45 broken away and showing my improved bracket applied with a clamp band to one of the side posts.

Fig. 2 is a horizontal cross sectional view taken through the center of the bracket.

Fig. 3 is a detail view of the flexible 50 clamping strip.

Fig. 4 is a detail front elevation of the metal bracket plate.

Fig. 5 shows the bracket plate reversed 55 and connected by center screws to a support.

Similar reference numerals refer to similar parts throughout the drawings.

As illustrated, I show my invention attached to a side post 1 of a metal bed frame

which, however, is typical of any square, 55 polygonal or round support to which it may be desired to attach my improved bracket. This bracket is intended to support a standard type of canopy frame which is illustrated in conventional form and comprises the 60 spring arm 2 and the head board extension 3 which are suitably joined at each side to the coils 4 from which lead the mounting loops 5 which are intended to be introduced in the bracket supports for the canopy 65 frame. My improved bracket support comprises a strip of sheet metal 6 provided with longitudinal parallel grooves 7 so as to receive the legs of a canopy frame loop 5. The side edges of the bracket are curved 70 convexly and provided with longitudinal parallel slots 8 formed by stamping tongues 9 outwardly from the outer face of the bracket. The tongue on each side is inclined towards the bracket center and the slots 75 8 are wide enough for the passage therethrough of a flexible band 10 which is inserted through both slots 8 and is adapted to pass outside of the legs of a loop 5 so as to draw them tightly into the grooves 80 7 which form seats therefor in the bracket. Moreover the tongues 9 engage the band on each side of the loop 5 and effectively brace it to restrain any lateral play of the loop 85 relatively to the bracket. When the band has been passed about the bed post or like support 1, it has its free ends drawn tightly together with a screw bolt 11, having thereon a wing nut 12.

If desired a strip of leather or fabric 13 90 may be glued or otherwise attached to the inner face of the bracket plate 6 with its ends free to be passed about and to protect the bed post or the like support from being scarred. The metallic strip 10 is provided 95 with a series of bolt holes 14 at each end for the reception of the bolt 11.

In operation, the metal band 10 is woven through the slots 8, and the canopy frame loop 5 is slipped into position with its legs 100 resting in the grooves 7. The bracket 6 is then applied to a bed post, the bolt 11 is inserted through the proper bolt holes 14, and a wing nut 12 is screwed tight, in doing which the band is applied to clamp rigidly 105 the bracket to the post and, what is of greatest importance, the bracket loop 5 is itself clamped by the band to the post so

that both parts are held rigidly in set position and the canopy frame cannot rattle or move, nor scar the bed post or other support.

In Fig. 5, I illustrate a further method of using my improved type of bracket plate 6 which is of special advantage when it is desired to apply the same to wooden bed posts or like supports 15. Here I provide the mounting screws 16 which are passed 10 through holes 17 therefor in the center of the plate which is reversed so that its tongues 9 are inclined rearwardly toward the support 15 and the heads of the screws engage against the concave central portion 15 of the plate. The legs of the mounting loop 5 are still engaged in the same grooves 7 but these grooves are now faced toward the support 15 and serve to hold the loop firmly 20 against the same. The shape of the bracket 25 and the position of the screws 16 enables the bracket to be drawn inwardly until it clamps the loops so tightly that the latter cannot yield or rattle, nor can it be disengaged without the removal of the screws 16.

My present bracket support can be shipped flat and is quite inexpensive as it requires no assembling.

My invention may be variously modified as to its details of structure within the scope 30 of the appended claims.

What I claim, is:—

1. A canopy frame support, comprising a rigid metal plate grooved to receive a canopy frame loop and having lateral slots, and a 35 flexible strip woven through the slots and adapted to pass over the loop and about a support element to clamp both the canopy

frame loop and the plate to the support element, substantially as described.

2. A canopy frame support, comprising a 40 metallic plate having side slots and out-turned inwardly inclined ears and longitudinal grooves having a raised portion between them parallel with said ears, and a flexible band adapted to be woven through 45 said slots and having means to clamp its ends together about a support, substantially as described.

3. In a canopy frame bracket, comprising a mounting plate having spaced seats to receive a canopy frame loop and a fastening means consisting of a flexible band adapted to embrace both the plate and loop as a support therefor, and means to tighten said band to clamp the loop to the plate and the 50 plate to the support.

4. A canopy frame bracket, comprising a metal mounting plate shaped to form alternate concave and convex surfaces, there being side slots and center screw holes adapted 60 to receive attaching means.

5. A bracket for canopy frames, comprising a metal plate of wave like cross sectional contour having longitudinal slots at each side formed by punching up inwardly inclined tongues, the spaced depressions in the plate being adapted to receive in them the legs of a canopy frame loop, and means to clamp the plate and loop to a support.

In testimony whereof I affix my signature, 70

CLINTON B. PIKE.
